ATTORNEYS.

UNITED STATES PATENT OFFICE

2,251,601

SPOUT

Claude Eugene Pope, Oakland, Calif.

Application October 7, 1938, Serial No. 233,887

2 Claims. (Cl. 221—23)

This invention relates to a new and useful combined punch and pouring spout capable of being applied to liquid containers to punch an opening in the same and to also provide means for readily pouring the liquid from the container after said opening has been punched therein.

The principal object of the present invention is to provide a combined punch and pouring spout that may be readily applied to any non-vitreous container of liquids, and when adjusted to position after the punching operation, will adjust itself to the punched container to facilitate the pouring of the liquid from the container.

Another object of the invention is to provide an article of the class set forth that includes a punch, a pouring spout, and means for retaining the combined punch and spout in pouring position upon the container.

A further object of the invention is to provide an article of the class set forth that is especially adapted to milk containers of non-vitreous character.

A still further object is the provision of an article of the type designated that is positive in action, that may be readily applied to any container of metal or paper, and that is very simple in construction and operation.

Other objects and advantages will be apparent during the course of the following description.

In the accompanying drawing forming a part of this specification and in which like numerals are employed to designate like parts throughout the same,

Fig. 1 is a side elevation of the device, showing the same applied to a paper milk container, and the view also discloses the article in pouring position;

Fig. 2 is a sectional detail of the improved device, showing the same applied to a paper milk container and in position for pouring the contents therefrom;

Fig. 3 is a plan view of the article per se, showing the retaining ring, punch element, and pouring spout; and

Fig. 4 is a sectional detailed view taken on the line 4—4 of Fig. 3 and further illustrating the configuration of the device.

It is obvious that the device illustrated may be applied to various non-vitreous containers of liquids, whether they be round, oval, or rectangular in shape, by slightly changing the configuration of the retaining ring. However, in the present application the same has been shown as applied to a milk container and will be described in connection with such a container.

The present device will function in connection with tapered or straight cylindrical bodies of the type disclosed. However, for the purpose of illustration the device has been shown as applied to a tapered type of milk container.

In the accompanying drawing wherein for the purpose of illustration is shown a preferred embodiment of my invention, the letter A designates the punch and spout of the device. The retaining ring is designated by the letter B, and the container by the letter C.

Figs. 1 and 2 show the device in operative position with the retaining ring surrounding the neck of the container and showing the spout in pouring position.

The punch and spout element A consists of a V-shaped trough 5 having an inwardly and downwardly extending V-shaped punch or tang 6 integrally formed therewith. The retaining ring B may be circular, oval, or substantially rectangular to fit over almost any configuration of container. The free ends 7 and 8 of the retaining member B extend under the V-shaped trough or spout and are preferably spot welded thereto, as shown in Figs. 2 and 3.

It will now be observed that when the device is applied to a liquid container, such as that shown in the drawing, the retaining ring B will encompass the neck of the container, and the spout element A will be manually moved downwardly until the tang 6 engages the scored tab 9 formed in the side of the container at the cream line thereof, which tang at this point when forced inwardly causes the said tab to be broken away from the wall of the container and to assume the position shown in Fig. 2, thus providing a pouring opening 10 in the container and positioning the spout A for pouring the contents of the container therefrom. The tang 6 in combination with the retaining ring B holds the spout in correct pouring position relative to the opening 10 thus formed in the container, and said ring assumes an angular gripping position upon the container, as clearly shown in Figs. 1 and 2.

It is, therefore, obvious that a combined device of this character may be utilized in connection with any container of liquids, which container may be punctured so as to provide a spout from which the liquid may be dispensed from the container in an expeditious manner and without spilling the same when dispensed from said container.

In Fig. 1 of the drawing the dotted line refers to the cream line of the container; and it is obvious that when the container is adapted to hold

milk, the cream can be readily poured through my improved spout.

In my co-pending application, Serial No. 214,124, filed June 16, 1938, I have disclosed a type of plug adapted to be used in milk containers, and I have further found that a type of spout and punch, as employed in the present application, has embodied therein considerable utility and serviceability.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. A utensil for directionally releasing the liquid from a round container, comprising means for encompassing such container including an ellipti-

cal ring having an elliptical axial dimension such that the ring engages side walls of the container and having a trough secured to said ring near the major axis thereof and extending outwardly therefrom and having a puncturing means in extension of said trough and deflected at an angle to the plane of the ring, for puncturing the container wall.

2. A utensil for directly emptying conoidal containers of their contents which comprises an elliptical ring for engaging the conical surface of such container at substantially opposed diametral points coincident with the minor elliptic axis and for pivoting therearound, a fluid channel member secured to said ring at one end thereof and directed radially outward thereof, said channel member extending inwardly of said ring and forming a container punch.
